UNITED STATES PATENT OFFICE.

ARVIN H. HOPPERT, OF ANN ARBOR, MICHIGAN.

PNEUMATIC ACTION.

1,087,769.

Specification of Letters Patent. Patented Feb. 17, 1914.

Application filed July 22, 1913. Serial No. 780,537.

To all whom it may concern:

Be it known that I, ARVIN H. HOPPERT, a citizen of the United States, residing at Ann Arbor, in the county of Washtenaw 5 and State of Michigan, have invented new and useful Improvements in Pneumatic Actions, of which the following is a specification.

The invention relates to player pianos, and 10 more particularly to the class of pneumatic actions for player pianos.

The primary object of the invention is the provision of a pneumatic which can be conveniently mounted in a pneumatic action 15 and has connection with a main air chamber wherein constant suction is maintained from the main bellows so that the pneumatic will instantly respond on the opening of its inlet for the accurate action thereof for controlling the hammers of the piano action in the automatic playing of the same.

Another object of the invention is the provision of a pneumatic action wherein the valve is actuated in a novel manner to assure 25 the proper piano action for the automatic playing of the piano.

A further object of the invention is the provision of a pneumatic action which is simple in construction, durable, compact, 30 capable of being conveniently installed above the keyboard for the direct connection with the piano or other action, and also which is inexpensive in manufacture.

The invention consists of novel features 35 and parts, and combinations of the same, which will be more fully described herein-after in detail and then pointed out in the claims hereunto appended.

In the drawings:—Figure 1 is a vertical 40 transverse sectional view of a piano showing the player and piano action with the pneumatic action constructed in accordance with the invention arranged therein. Fig. 2 is a fragmentary plan view of several of the 45 pneumatics. Fig. 3 is a sectional view on the line 3—3 of Fig. 2. Fig. 4 is a sectional view on the line 4—4 of Fig. 3. Fig. 5 is a horizontal sectional view on the line 5—5 of Fig. 4.

Similar reference characters indicate corresponding parts throughout the several views in the drawings.

Referring to the drawings in detail, the main suction chamber A is connected with 55 the main bellows B through the medium of a tube C, and fixed to the top of the suction

chamber A is the supporting plate 5 of each pneumatic 6, which has its movable member 7 connected with the abstract 8 of the piano action. The abstract 8 engages the wippen 9 60 of the piano action so that when a pneumatic 6 collapses, then a swinging motion is given to the wippen 9 to actuate the corresponding hammer with a view of sounding the desired string. By the arrangement described the piano can be readily played by hand without interference with the pneumatic action.

Each pneumatic 6 comprises a fixed member 10 to which is connected the movable 70 member 7, and is formed with a chamber 11 disposed vertically therein, one end of which is closed by the plate 5 while its opposite end is closed from the bellows 13 of the movable member 7 of the pneumatic, the chamber 11 75 being fitted with a brass guide tube 14 in which is held a piston 15, the stem 16 of which extends through an aperture 17 in the closed end of the chamber 11 and projects into the bellows 13, the projected end of the stem 16 being detachably connected to a rocker arm 18 preferably made from aluminum, the same being formed with a medial fulcrum rib 19 and is supported upon a pivot 20 fixed in the inner face of the stationary member 10 of the pneumatic.

The stationary member 10 of the pneumatic is formed with a suction vent 21 which opens directly into the bellows 13 of the said pneumatic and also communicates directly 90 with the main suction chamber A. Also this stationary member 10 is formed with vents 22 and 23, the latter leading from the atmosphere to the bellows 13, while the vent 22 communicates with the lower end of the chamber 11 and is connected through the medium of a nipple 25 mounted in said vent with an air inlet tube 26 leading from the tracker board 27 of the player action, the vents 21 and 23 being surrounded by means 100 of pads 24 against which work the opposite ends of the rocker arm 18 which are designed to close the respective vents 22 and 23 for controlling the action of the pneumatic. The tracker board is perforated as 105 usual to correspond with the number of tubes 26 so that on the travel of the music sheet over the said tracker board 27 the music note perforations in the sheet will register with the respective perforations in the 110 tracker board so as to permit the intake of air therethrough on the working of the

player action for the operation of the pneumatics 6 which control the wippen 9 of the piano action, whereby the hammers thereof will be forced against the strings of the piano for the sounding thereof, thereby automatically playing the said piano.

Opening into the upper end of the valve chamber 11 is a port 28 which communicates directly with the main suction chamber 10 A, the latter being subject to a constant suction from the main bellows B when operated so that when the inlet tube 26 is open for the intake of air through the tracker board 27 the suction in the port 28 will cause the lifting of the piston 15, thus rocking the rocker arm so that the vent 21 will be placed in direct communication with the main suction chamber A and simultaneously therewith the rocker arm 18 will close the vent 23 to the atmosphere and coincident therewith the bellows 13 will be caused to collapse, thereby lifting the movable member 7 which in turn actuates the hammer of the piano action for the sounding of a note by the same striking a string.

The vent 23 opens through one side of the stationary member 10 of the pneumatic, and as heretofore stated is controlled by the rocker arm 18 so that it will be opened or closed thereby. The said vent 23 when the bellows 13 of the pneumatic 6 is collapsing is closed, thereby avoiding the admission of air through the vent 23 from the atmosphere to the pneumatic.

Adjustably threaded in the stationary member 10 of each pneumatic 6 is a regulating screw 29 which limits the collapsing of the bellows 13 of the pneumatic 6, thereby regulating the extent of movement of the member 7 of the said pneumatic, thus controlling accurately the action of the hammers, and when this bellows 13 is extended air is sucked in from the atmosphere through the vent 23 so that the extending of the said bellows is not impeded. The piston 15 is arranged in the chamber 11 of the stationary member 10 of the pneumatic 6, while the rocker arm 18 is mounted on the stationary member 10 and is located within the bellows 13 and is adapted to control the vents 21 and 23 respectively, which are staggered with relation to each other.

When a tracker board perforation is uncovered and air passes through the tracker board perforation the vacuum in the piston chamber 11 below the piston 15 is relieved so that the said piston 15 will be raised by the suction from the main suction chamber A through the port 28 and simultaneously the rocker arm 18 will be rocked, uncovering the suction vent 21 so that direct communication is established between the said suction chamber A and the bellows 13, thereby creating a suction within the bellows 13 and causing the collapsing of the same. When the vent

21 is open the vent 23 is instantly closed to atmospheric pressure, at which time the interior of the pneumatic is in communication with the suction chamber A so that the pneumatic is collapsed and consequently the rocker arm 8 is moved to actuate the wippen 9 for actuating the hammer and sounding the proper string. As soon as the tracker board perforation is closed by the note sheet the bellows 13 of the pneumatic 6 is shut off from communication with the main suction chamber A and atmospheric air is taken in through the port 23 provided in the stationary member 10 of the pneumatic, thereby permitting the previously collapsed pneumatic to become extended or returned to normal open position.

The driving mechanism of the note sheet, the tracker board, the piano action, and the main bellows of the pneumatic action are of any ordinary well-known construction and are operated in any ordinary well-known manner. The construction of the pneumatic and the manner of mounting the same on the main suction chamber avoids utilizing considerable space and enables the said pneumatic to be conveniently and easily mounted in the piano to assure compactness and also avoids the necessity of the use of long tubes leading from the tracker board to the pneumatics, thus reducing the expense and decreasing the danger of leakage between the pneumatic action and the tracker board, and also assures a very quick action of the pneumatics for the latter open and collapse almost instantly.

From the foregoing it is thought that the construction and manner of operation of the device will be clearly understood, and therefore a more extended explanation has been omitted.

What is claimed is:—

1. The combination with a suction chamber, of a pneumatic action comprising a stationary member, a bellows carried by the stationary member, the said stationary member being provided with a piston chamber having communication with the suction chamber, the said stationary member being provided with a vent leading from the suction chamber to the bellows, the said pneumatic being further provided with vents one of which leads from the bellows to the atmosphere and the other from a tracker board to the piston chamber, a rocker arm fulcrumed within the bellows and adapted to alternately close the suction vent and atmospheric air inlet vent, and a piston movably held within the piston chamber and connected with the rocker arm for actuating the same.

2. The combination with a suction chamber, of a pneumatic action comprising a stationary member, a bellows carried by the stationary member, the said stationary mem-

ber being provided with a piston chamber having communication with the suction chamber, the said stationary member being provided with a vent leading from the suction chamber to the bellows, the said pneumatic being further provided with vents one of which leads from the bellows to the atmosphere and the other from a tracker board to the piston chamber, a rocker arm 10. fulcrumed within the bellows and adapted to alternately close the suction vent and atmospheric air inlet vent, a piston movably held within the piston chamber and connected with the rocker arm for actuating the same, and adjustable means mounted on the stationary member for regulating the collapsing action of the bellows.

3. The combination with a suction chamber, of a pneumatic action comprising a stationary member, a bellows carried by the stationary member, the said stationary member being provided with a piston chamber having communication with the suction chamber, the said stationary member being 20. provided with a vent leading from the suction chamber to the bellows, the said pneumatic being further provided with vents one of which leads from the bellows to the atmosphere and the other from a tracker board to the piston chamber, a rocker arm fulcrumed within the bellows and adapted to alternately close the suction vent and atmospheric air inlet vent, a piston movably held within the piston chamber and connected with the rocker arm for actuating the same, adjustable means mounted on the stationary member for regulating the collapsing action 25. of the bellows, resilient pads mounted about the suction and atmospheric vents and engaged by the ends of the rocker arm, and a fulcrum rib formed on the rocker arm and working against the stationary member for assuring the proper degree of rocking action of the arm.

30. In testimony whereof I affix my signature in presence of two witnesses.

CLEO E. HOFFMAN.

of the bellows, and resilient pads mounted about the suction and atmospheric vents and engaged by the ends of the rocker arm. 40

4. The combination with a suction chamber, of a pneumatic action comprising a stationary member, a bellows carried by the stationary member, the said stationary member being provided with a piston chamber 45 having communication with the suction chamber, the said stationary member being provided with a vent leading from the suction chamber to the bellows, the said pneumatic being further provided with vents one 50 of which leads from the bellows to the atmosphere and the other from a tracker board to the piston chamber, a rocker arm fulcrumed within the bellows and adapted to alternately close the suction vent and atmospheric air inlet vent, a piston movably held within the piston chamber and connected with the rocker arm for actuating the same, adjustable means mounted on the stationary member for regulating the collapsing action 55. of the bellows, resilient pads mounted about the suction and atmospheric vents and engaged by the ends of the rocker arm, and a fulcrum rib formed on the rocker arm and working against the stationary member for assuring the proper degree of rocking action of the arm.

In testimony whereof I affix my signature in presence of two witnesses.
